UNITED STATES PATENT OFFICE

2,545,724

APPLICATOR FOR HEAT MANIPULATION
OF THE EYES

Cecil Claud Curtis, Washington, D. C.

Application June 8, 1948, Serial No. 31,675

2 Claims. (Cl. 128—399)

1

This invention relates to an applicator for heat or cold manipulation of the eye in securing a comforting or easy feeling thereof as in cases of congestion, by manipulation of the eye-lid and/or ball of the eye, attended by heat or cold or alternative treatments under heat and cold to improve the blood circulation through the eye, or the freedom of the muscles controlling the shifting movements of the eye.

In a companion application for patent, executed of even date herewith, the relatively comprehensive or broad invention underlying the manipulator of the instant invention, in reference to heat or cold treatments, as well as in a more specific application also executed of even date herewith, devoted to a heating means specifically, the phases of the structure apart from eye treatment are claimed. Differentiated from the same the present case will include claims to the eye treating phase exclusively.

The object of the instant case is to provide an implement capable of easy grasp or gripping in the hand of the operator, carrying either a heating or cooling medium, accessible to the interior of a treating head carried by the grip or handle, said head being constituted to enfold or engage over the eye lid with a pressure as exerted by the operator and shifted or moved with the engaged lid while manipulated to roll or move the eyeball, simulating a massaging function, whereby such action under the desired thermal or cold influence as the case may be, will stimulate the blood circulation to the eyeball and normal muscular movement of the eye to benefit the ailing conditions thereof.

The invention further comprises the special shaping of the lip or edge of the engaging face of the treating member to secure a firm grasp of the surfaces or member or members being treated; and a means of communication between the interior of the treating member and the interior of the handle or grip containing the heating or cooling medium whereby, at least in the instance of heated air, the same may be delivered in contact with the eye lid to correspondingly transmit heat thereto and adjacent parts of the eye.

Still another feature of the invention comprises the provision of differently colored discs or inserts of transparent plastic in a portion of the implement casing in proximity to an electric light bulb, for example, so that when the implement is being used in connection with heat treatment the illumination or glow may be seen through these discs or inserts, indicating the operative state of the implement. Importantly here, these

2

differently colored discs or inserts are intended for use under the illumination thereof in testing the eyes as to color, in ascertaining what is commonly called color blindness. When performing that function, however, the instrument will, of course, be held away from the patient, that is, not in contact with the eye as hereinbefore prescribed in the treating of the eye.

In the accompanying drawings the preferred embodiment of the invention is illustrated in connection with both heat and cold applications, and the same will be readily understood from an inspection of said drawings in connection with the specification hereafter contained.

15 In the said drawings:

Figure 1 is an outside view of the complete device.

Figure 2 is a longitudinal central sectional view through the same combined with the cartridge or container therewith for delivering a cold medium to the operating head.

20 Figure 3 is a similar view of a slightly modified form associated with a heating medium located interiorly of the device.

25 Figure 4 is a side view of the removable threaded or head member of the device.

Figure 5 is a longitudinal sectional view of the member shown in Figure 4.

Referring more specifically to the drawings 30 wherein like reference characters designate corresponding parts in the several views 6 represents the handle or grip portion of the device, the same being hollow or tubular to present a passage 7 longitudinally therethrough from its inner end to a relatively enlarged chamber 8, for the reception of a cartridge or container 9, for a cooling medium, extending into a hollow or dome-shaped head 9' connected to the grip or handle 7 by a threaded connection 10 permitting an adjustment 35 between the head portion 9' and grip 7 to oppose a breakable sealing cap 11 against a pointed or beveled deflector 12, at the top of the dome to effect opening of the container 9 and the escape of the cooling contents therefrom to the dome when it is desired that an eye piece 13, projected 40 above and integral with the dome, be manipulated in cold state.

The eye piece 13, with its integral carrying dome or head member 9', is formed of steel or 45 aluminum or other suitable metal. The eye piece is generally of oval outline or contour conforming to the shape of the eye to be treated and dished or concaved in its interior, as at 14, the working or engageable surrounding rim or edge portion 50 being beaded as at 15 to afford an inwardly dis-

posed edge portion 16 to contact the eye lid, when the implement is manipulated under light pressure to that end, to manipulate the eyeball in keeping with the movement of the implement. In this manner an ailing eye under treatment will be eased and stimulated and the circulation of blood through the eye, as well as the easing of the muscles of the eye, accomplished. The head or dome 9' has small escape apertures 17 to permit the eventual exhausting of the cooling medium delivered to the dome and effective on the eye piece 13.

In the embodiment of the invention illustrated in Figure 3, a heating medium for the dome or eye piece is illustrated, the same comprising the cylindrical grip or handle 18, containing a heating means 19, comprising an insulating body held in the grip or handle 18 between a shoulder 20 in said grip and a removable threaded ring 21 engaged with the outer end of the handle, the tubular member 19 being designed to contain the customary or preferred electric wiring (not necessary to be illustrated herein) supplying current to a lamp comprising an incandescent light bulb 22, arranged to project at least in part into the dome or head 23, formed like and similar in shape to the dome 9' of the embodiment of Figure 2 with this variation:

Instead of having a means in the dome to upset or break the seal of the cartridge or container 9 and completely closing the top of the dome (Figure 2) the present instance (Figure 3) may have an aperture 24 permitting heat from the lamp 22 to pass into the eye piece 25 to heat the eye lid when the implement is applied thereto and manipulated in addition to having the heat from the lamp conducted through the metal of the sides and top of the dome and to the eye piece 25 to effect heating of the latter. The eye piece is formed with an inwardly disposed bead 26 at its engaging edge and has the concaved formation and oval contour hereinbefore described in the case of the embodiment illustrated in Figure 2. There is also a small outlet or bore 27 from the interior of the dome, if and when found expedient.

In either or both of the embodiments of the invention illustrated in Figures 2 and 3, as hereinabove set forth and where the heating element is through the medium of an electric lamp or equivalent, it is useful to provide the dome 9' or 23 with inserts at spaced intervals around the dome in the nature of differently colored transparent discs 28, having screw-threaded engage-

ment with complementary threaded apertures 29, passing through the dome wall whereby the light or glow from the lamp 22 will shine through the transparent discs 28 and illuminate the respective colors provided thereby, advantageous in the testing of eyes for so-called color blindness, etc.

At the inner end of the handle or grip 6 of the form shown in Figures 1 and 2 there is provided 10 a valve plug 30, for the purpose of enabling the use of a storage medium located remote to the implement, to be used if desired in lieu of a cartridge or container 9 containing carbonic acid gas, for example, but inasmuch as this member 30 constitutes the subject matter of one of the other applications hereinabove referred to at the outset of this specification the details of the same will not be illustrated or described herein.

I claim:

- 20 1. An eye treating implement comprising a hollow handle for containing a battery and an electric lamp, an elongated closure cap of heat conducting material having threaded engagement with the handle into which a part of the electric lamp extends to transmit heat to the walls of said cap, and an eye cup of heat conducting material integrally formed with the cap to conduct the heat from the cap to the eye being treated, said cap being provided with openings therein to permit the free circulation of air into the cap, through the same and into said eye cup.
- 25 2. An eye treating implement comprising a hollow handle containing a battery, an electric heating element in circuit with the battery, an elongated closure cap of heat conducting material having threaded engagement with the handle into which the electric heating element extends to transmit heat to the walls of the cap, and an eye cup of heat conducting material formed integrally with the cap to conduct the heat from the cap to the eye being treated.
- 30 35 40
